SNOWSHOE HARNESS

Edward J. Balcomb, Stambaugh, Mich.

Application January 13, 1944, Serial No. 518,043

12 Claims. (Cl. 36—4.5)

This invention relates to improvements in snowshoe harness.

It is a primary object of the invention to provide novel, safe and improved means for removably securing a snowshoe to the wearer's foot in such a manner as to relieve the foot of all constricting pressure, to leave the foot full flexibility of movement respecting the snowshoe, and to provide for the instant disengagement of the snowshoe in the event of emergency.

Other objects of the invention will be apparent to those skilled in the art upon analysis of the following disclosure of the invention.

In the drawing:

Fig. 1 is a plan view of a snowshoe with my improved harness or binding applied thereto.

Fig. 2 is an enlarged detail view of the harness or binding in section, portions of the snowshoe also being illustrated in section.

Fig. 3 is an enlarged detail of the harness in perspective.

Fig. 4 is a fragmentary detail in plan showing the connection of the harness with the shoe.

Like parts are identified by the same reference characters throughout the several views.

Application of a harness or binding to a snowshoe is complicated by the fact that it must be secured to a portion of the shoe which does not have inherent rigidity. It is desirable that the connection of the wearer's foot to the shoe should be secure against relative movement in some directions, but should have complete flexibility to permit the wearer's foot to tilt in walking. The present invention not only provides for such complete flexibility but does so in a way which does not constrict free blood circulation in the foot and, moreover, permits the natural tilting movement of the foot to be used to promote better traction.

The snowshoe is of conventional design including a frame 5 laced with rawhide thongs at 6, 7 and 8. The rear anchorage of the thongs into area 8 is provided by a cross brace 9. The forward anchorage of the thongs in the area 6 is provided by a heavy transversely extending multi-ply rawhide strap at 10. Between the strap 10 and the cross brace 9 is an opening 11.

All of the foregoing is conventional in snowshoes.

Instead of using any strap which crosses the toe of the wearer's boot or shoe, I provide at 15 a skeletonized toe-receiving basket or pocket comprising a fulcrum rod 16 which passes beneath the ball of the user's foot and to the ends of which the arcuate wire 17 is connected to make a D-shaped frame large enough to receive the boot or shoe without constriction.

The general position of the frame comprising members 16 and 17 is in a vertical plane. To this frame is connected another generally

arcuate wire at 18 in a substantially horizontal plane, preferably slightly above the level of the fulcrum rod 16. Strut wires 19, 20, 21 connect the fulcrum rod 16 with the central portion 22 of the horizontal frame member 18. This portion 22 of the arcuate frame member is spanned by a vertical arch 23 from which the arcuately formed top frame members 24, 25 extend to the upper central portion of the arcuate frame member 17. Other arcuate frame members 26, 27, 28, 29 complete the enclosure by extending at intervals between member 17 and member 18. While not at all essential to the invention, all parts of the wire or rods used in the manufacture of the basket or pocket may be wound with rawhide, or otherwise covered, the rawhide binding being represented at 30.

The form of the member 18 is such that one side of it is almost straight, most of the curvature being in the other side. Thus this device is made in "rights" and "lefts" in general conformity with the shape of the toe portion of the wearer's boot or shoe. Thus, it is the sole, rather than the upper of the wearer's boot or shoe, which engages the cage or pocket to position the wearer's boot or shoe on the snowshoe.

The connection of the cage or pocket to the snowshoe is effected as follows:

The pintle rod 16 is provided, preferably throughout all exposed portions of its length, with sleeves 32, 33, 34, 35 in which it has oscillatory bearing. These sleeves are then lashed by means of rawhide thongs 36 in a figure 8, to the cross strap 10 of the snowshoe. Since the sleeves 35 are thus securely held against either vertical or lateral displacement with respect to the snowshoe, and are incapable of relative axial movement along the pintle rod 16, the boot receiving cage cannot move either vertically or laterally respecting the snowshoe. It can, however, pivot with almost no resistance whatever by oscillatory movement of the rod 16 in the several bearing sleeves 32, 33, 34, 35. Thus, a normal movement of the foot in walking is readily accommodated.

The forward portion of the boot or shoe of the user is held into the cage or pocket above described by an elastic safety strap 38 engaged at its ends in buckles comprising the D rings 39 and slides 40, the D rings being connected to the basket or cage by links 41, 42, 43 rigidly welded or otherwise connected between the D rings and the cage. As shown in Fig. 2, the end of the strap 38 is passed about the slide bar 40 and thence between the slide bar and the end of the D ring so that when once adjusted with the right tension to the wearer's foot no further adjustment is necessary for applying or removing the snowshoes. Under tension of the strap, 60 the end is firmly clamped in the buckle.

While the strap 38 may be of any desired material and may be rendered elastic through the use of springs, if desired, it is preferred to use a rubber strap. In any event, the strap passes about the wearer's foot at approximately the level of the shoe sole and is engaged about the heel of the boot or shoe without engaging any portion of the boot or shoe where construction and restriction of blood circulation might result.

The tension of the strap 38 is exerted forwardly upon the boot or shoe to force the toe portion thereof into the cage or pocket where, as above noted, the pressure is absorbed between the sole portion of the boot or shoe and the cage. Thus, while the boot or shoe is tightly and securely held to the snowshoe, this result is achieved without any binding effect whatever across the wearer's foot.

An important feature of the invention lies in the fact that the boot or shoe may be instantly disengaged from the harness by simply exerting relative rearward pressure upon the elastic strap 38. In the use of conventional snowshoe harness, serious accidents sometimes result due to the permanent connection of the wearer's footwear to the snowshoe. With the safety harness of the present invention, if the snowshoe catches on a stub or other firm object which penetrates the mesh, as the foot is raised for the next step, the elastic strap 38 yields upwardly and rearwardly, the basket dropping downwardly from the toe of the boot, then automatically releasing the boot and allowing the wearer to walk ahead free of the snowshoe. But in the event of a fall, the release of the harness is easily effected by simply stretching the elastic strap 38. This avoids the difficulties experienced in the use of the conventional harness where, in the event of a fall, the wearer may be unable to reach and release the harness and he may not be able to rise without releasing the harness. The release of the harness is easily effected by simply stretching the elastic strap 38.

To assist in attaining traction on ice and the like, I prefer to provide the forward portion of the cage or basket with downwardly directed prongs at 45 which, when the heel of the wearer's boot or shoe is normally resting on the snowshoe, will be retracted above the level of the snowshoe frame, as indicated in Fig. 2. It will be apparent, however, that as the wearer moves forward as in walking, the tilting of his foot will cause the cage of the harness to tilt or oscillate on the pintle rod 16 thereby forcibly urging the prongs 45 into or against the underlying surface. Thus excellent traction is assured under all conditions.

I claim:

1. A snowshoe harness comprising a boot receiving cage having a transverse pintle rod positioned to lie beneath the boot and a bearing sleeve mounted on said rod and adapted for connection with the snowshoe.

2. The device of claim 1 in which said cage comprises means engaging the ends of the sleeve whereby to preclude axial displacement between the sleeve and rod.

3. The device of claim 1 in which the cage is provided forwardly of said rod with downwardly projecting traction prongs.

4. A snowshoe harness comprising the combination with a cage adapted to receive the forward portions of a boot, of an elastic strap having its ends connected with the cage and having

an intermediate portion extending rearwardly therefrom to encircle a boot or shoe and to urge the same into the cage.

5. In a snowshoe harness, the combination with a cage adapted to receive a boot and comprising means conforming to the outline of the forward portion of the sole of the boot to receive the forward thrust thereof, and means comprising a strap connected with opposite sides of the cage and extending thence rearwardly to engage a boot having its toe portion in the cage, said strap being substantially horizontal and substantially at the heel level whereby pressure of the strap upon the boot is transmitted through the sole portions of the boot to the cage to locate the boot respecting the cage without any pressure on the boot upper or the wearer's foot.

6. The device of claim 5 in which the cage is provided with a mounting upon which it is pivotable forwardly and rearwardly in a vertical plane.

7. The device of claim 5 in which the cage is provided with a mounting upon which it is pivotable forwardly and rearwardly in a vertical plane, said cage having at its forward portion downwardly directed prongs adapted in the pivotal movement of the cage to engage an underlying surface.

8. The combination with a snowshoe having a frame and webbing, the webbing being arranged in sections, two of which are spaced to provide an opening, the rearward section adjacent said opening being provided with transverse means to which said webbing is connected, at least one sleeve connected with said means, a cage including a pintle bar, said bar extending through said sleeve in pivotal connection through said sleeve with said means, and a strap device for holding a wearer's boot with its toe portion engaged in said cage for pivotal movement respecting the snowshoe.

9. The device of claim 8 in which the cage is provided forwardly of said pintle bar with downwardly directed prongs.

10. The device of claim 8 in which the strap device is elastic and under tension in its engagement with a wearer's boot.

11. In a snowshoe harness, the combination with a cage adapted to receive the forepart of a wearer's boot, of a pair of buckles connected with the cage, each comprising a D ring and a cross slide bar and a tension strap having its ends engaged about said cross slide bar and thence between said bar and the D ring, said strap being elastic.

12. In a snowshoe harness, the combination with a series of axially aligned sleeves, of a cage comprising a pintle bar extending through the several sleeves, an arcuate frame member disposed in substantially a vertical plane and connected at its ends with said bar and confining the ends of the series of sleeves against outward displacement, a generally horizontal arcuate frame member, boot confining wires extending arcuately between said frame members, and at least one boot supporting wire extending from a forward portion of the horizontal arcuate frame member and an intermediate portion of said rod, being connected with said rod between the sleeves of said series, the rod and cage being unitarily pivotal in bearings provided by said sleeves.
